UNITED STATES PATENT OFFICE.

GEORG GRABE, OF NIKOLASSEE, NEAR BERLIN, GERMANY, ASSIGNOR TO SIEMENS & HALSKE AKTIENGESELLSCHAFT, OF WERNERWERK, SIEMENSSTADT, NEAR BERLIN, GERMANY.

AUTOMATIC TELEPHONE SYSTEM.

Application filed December 18, 1922. Serial No. 607,471.

To all whom it may concern:

Be it known that I, GEORG GRABE, a German citizen, and a resident of 17 Sudenstr., Nikolassee, near Berlin, Germany, have invented certain new and useful Improvements in Automatic Telephone Systems, of which the following is a specification.

The present invention relates to circuit arrangements for telephone systems with automatic working, in which numerical switches (e. g., group selectors) have access to large groups of lines, wherein current impulses occur when a large number of intermediate switches, that are standing on engaged lines, are moved on, these impulses having a deleterious effect on the battery.

Now the object of the present invention is to avoid this deleterious effect on the battery, this being achieved by moving on in groups the intermediate switches standing on engaged lines.

This general solution of the invention is effected in that the movement of the intermediate switches is controlled over a special switching device, which is dependent on switching means at the intermediate switches.

The drawing shows in a simple diagrammatic manner one method of carrying out the invention. In Figure 1 the calling subscriber is marked A, he can reach a group selector D over a line switch C. Figure 2 shows a continuation of Figure 1, in it E designates an intermediate switch accessible by a group selector D, W designates a switching device (stepping switch, auxiliary switch) which is common to the intermediate switches, and F designates a group selector located beyond the intermediate switch.

The method of operating an installation according to the invention will now be described. When the subscriber A takes down his receiver the circuit for the line relay 2 of the line switch C is closed. The relay 2 is energized and at its lower contact closes a circuit for the switching relay 3 and the rotary magnet 4 of the line switch C. As is indicated by the solid black upper portion of relay 2, the copper slug by means of which this relay is made slow acting is placed on the armature end of the relay and therefore prevents the armature from becoming attracted until the core of the relay has become sufficiently saturated to enable it to hold up a sufficiently long interval after

the circuit is subsequently opened by relay 3, as pointed hereinafter (the usual position of the copper slug on the heel end of slow acting relays, such as 9 and 10 of switch D, being indicated by a shaded portion at the lower end of their respective cores). If the wipers of the line switch C rest on an engaged line leading to a group selector, earth potential is connected to the test wiper 5, whereby the relay 3 is short circuited and the rotary magnet 4 receives the full pressure, so that it operates and rotates the wipers 5, 6 and 7. As soon as a free line is found the relay 3 is energized. It operates its contacts and at its upper and lower contacts opens the circuit for the relay 2. The calling subscriber's line is now connected with the group selector D, whereby the circuit is closed for the relay 8. The relay 8, at its contact connects up the slow releasing relay 9, which connects up at its upper contact 20 earth potential to the test wiper 5, thus marking the line engaged, and at its lower contact prepares the circuit for the relay 10 and the lifting magnet 11 of the group selector D. The calling subscriber now operates his number dial and thus transmits a train of impulses corresponding to the first digit of the wanted subscriber's number. The relay 8 is de-energized a number of times corresponding to the train of impulses, and at its contact repeats the impulses to the relay 10 and lifting magnet 11, the circuit of which was prepared at the lower contact of relay 9. The relay 10 remains energized during the impulse transmission and during this time maintains energized the following circuit: earth, contact 20 of the relay 9, contacts 12 and 13 of the relay 10, off-normal contact 14 (closed at the first lifting step), winding 95 of relay 15, battery, earth.

The relay 15 at its contact 16 prepares a circuit for the rotary magnet 17 of the group selector D, and locks itself over its contact 18 and the contact 19 of the rotary magnet 17. The relay 10 is de-energized at the end of the train of impulses, closes its contacts 12-21' in the circuit prepared for the rotary magnet 17: earth, contact 20 of the relay 9, contact 12-21' of the relay 10, contact 16 of the relay 15, winding of the rotary magnet 17, battery, earth. The rotary magnet 17 moves on the wipers one

step, and at its contact 19 opens the circuit for the relay 15, which is de-energized, and by opening its contact 16, interrupts the circuit of the rotary magnet. The test wiper 21 now moves on to the test contact of the first trunk line leading to an intermediary switch E. The rotary magnet 17 is de-energized and has again closed its contact 19 so that the following circuit for relay 15 is established: earth, battery, winding of the relay 15, off normal contact 14, contact 19 of the rotary magnet 17, contact 22-23 of the relay 26, test wiper 21 and contact 24 of the group selector D, test lead 25, upper winding of relay 30, test wiper 35 of the intermediary switch E. Assuming that the intermediary switch E is free but that the trunk line taken into use by it is engaged, earth potential then lies on the test contact and on the test wiper 35. The circuit for relay 15 is thereby established, so that it is energized and at its contact 16 again closes the circuit for the rotary magnet 17, whereby the wipers of the group selector D are moved on one contact, and are thus switched on to the next trunk line leading to an intermediary switch E. This switching operation is repeated until a free intermediary switch E is found, which has been set on a free trunk line leading to a second group selector, F.

Assuming that such an intermediary switch E, set on a free trunk line, has been found at the test contact 24, then a circuit is closed for the switching relay 26: earth, contact 20 of the relay 9, winding of the relay 26, contact 19 of the rotary magnet 17, off normal contact 14, winding of the relay 15, battery, earth. The relay 15 cannot be energized in this circuit because the relay 26 has a high ohmic resistance. The relay 26, which at its contacts has switched through the connection as far as the intermediary switch E, cannot operate before the short circuit has been removed from its winding (this has been set up by the potential earth, which has been extended back through the test wipers of the engaged intermediary switches similar to E). The operation of relay 26 connects earth potential automatically to the test wiper 21, whereby the following circuit is closed: earth, contact 20 of the relay 9, closed front contact 23 of the relay 26, test wiper 21 and contact 24 of the group selector D, lead 25, low resistance winding of relay 30, winding of the relay 33, battery, earth. A second high resistance winding of relay 30 is connected in parallel to this circuit over the high resistance 36. The windings of relay 30 are so connected that they assist one another. The relay 30 at its contacts 37 and 38 connects through the speaking leads, whereby a circuit is closed for the impulse relay 44 of the succeeding group selector F.

Furthermore the relay 30 connects itself at contact 39 in the following circuit: earth, contact 20 of the relay 9, contact 23 of the relay 26, wiper 21 and contact 24, lead 25, its own contacts 40, 41 and 39, high resistance winding of the relay 30, battery, earth, and the relay 33 is now connected up over contacts 40 and 41 of relay 30, battery, earth. As soon as the impulse relay 44 operates it connects up the releasing relay 42. The latter at contact 43 connects earth to the release lead and wiper 35, whereby the relays 30 and 33 are maintained energized and thus the switches C and D are maintained in their operated position. The group selector F is now operated in the same manner as the group selector D.

If a number of intermediary switches E are engaged and the free intermediary switches stand on engaged lines leading to succeeding group selectors, the relays 33 and 34 individual to separate intermediary selectors are energized by earth potential on the test lead 25 and on the wiper 35. Thereby the circuit extending over the serially connected contacts of these relays is closed for the common starting relay 32. This closes at its contact 63 the circuit for the rotary magnet 45 of the stepping switch W which is in the normal position: earth, contact 63 of the relay 32, bank contact 52 and wiper 46 of the stepping switch W, winding of the rotary magnet 45, self interrupter 62, battery, earth. The rotary magnet 45 is energized in this circuit and causes the wipers 46 and 48 of the stepping switch to leave their normal position and to move on to the first contact. If it is assumed that the intermediary switch E is free, but its outgoing trunk lines are engaged, the following circuit for the rotary magnets of the first group of intermediary switches is closed over the first contact 54, and the wiper 48, as soon as the wipers 46 and 48 are set on their first contacts: earth, battery, winding of the relay 47, wiper 48 and contact 54, self interrupter and winding of the rotary magnet 31, back contact 41 of the relay 30, wiper 35, bank contact, on which the intermediary switch stands, test lead of the engaged line, earth. The slow acting relay 47, located in this circuit, is energized and opens its contact 64, whereby the new circuit for the rotary magnet 45 of the stepping switch W is opened. Hence the wipers of the stepping switch W remain in the position 1. If all the free intermediary switches of this group have reached a free trunk line, there is no earth potential on the test lead. The motor magnets 31 and the slow acting relay 47 in the motor magnet circuit are therefore de-energized. The relay 47 again closes its contact 64, so that the circuit of the rotary magnet 45 of the stepping switch W is established: earth, contact 61 of the relay 59, back

contact 64 of the relay 47, bank contact 65 and wiper 46, rotary magnet 45, self interrupter 62, battery, earth. The rotary magnet 45 operates and moves the wipers 46 and 48 on to the second contacts 66 and 67. Thereby the motor magnets of the second group of intermediary switches are connected up over the wiper 48, contact 67 and the lead 49, it being understood, of course, that the switches similar to E under the control of whose test wipers the circuit of relay 32 is initially completed have been arbitrarily divided into groups as regards the circuits of their motor magnets. In this circuit the relay 47 again operates, so that the circuit for the rotary magnet 45 of the stepping switch is opened. The stepping switch W is stopped. The free intermediary switches of the second group, which are standing on engaged lines are set on free lines in the manner before described. When this has been effected the relay 47 is de-energized, it closes its contact and thereby again establishes the circuit for the rotary magnet 45 of the stepping switch W. The wipers 46 and 48 of the stepping switch are set on the third contacts 68 and 69. The stepping switch W is again stopped, the motor magnets of the free intermediary switches accessible over the line 51 obtain current and set themselves on a free line in the manner described. This operation is repeated until all free intermediary switches in the several groups have been set on free lines, or until the stepping switch W has made a complete revolution and has returned to its normal position. When the wipers 46 and 48 reach their normal position the circuit extending over the bank contact 52 and wiper 46 to the rotary magnet 45 of the stepping switch W is opened, since the relays 33 and 34 individual to separate intermediary switches E have deenergized—because the associated switches have stepped to idle contacts—and have opened the circuit for the common starting relay 32 so that the latter opens the circuit of the rotary magnet and stops the stepping switch W.

If all the intermediary switches E or all the lines leading from the intermediary switches to the succeeding group selectors are engaged, the switching relays 58 at the succeeding group selectors have been energized in known manner and have opened their contacts 53, or 55, 56, 57, whereby a short circuit is removed from the relay 59 associated with the stepping switch, so that it is energized over: earth, winding of the relay 59, resistance 60, battery, earth. The relay 59 opens its contact 61 and thus interrupts the circuit for the motor magnet 45 of the stepping switch W. Thereby the continuous rotation of the wipers of the step-

ping switch W is prevented if all the lines leading to succeeding group selectors are engaged.

What I claim and desire to protect by Letters Patent is:—

1. In a telephone system, a plurality of automatic trunk hunting switches divided into groups, and means common to said switches for advancing the idle ones from busy trunks to idle trunks, one group at a time. 75

2. In a telephone system, a plurality of automatic trunk hunting switches, means common to said plurality of switches and normally ineffective for bringing all the idle ones of said switches into engagement with idle trunks, means for rendering the last named means effective, and other means for maintaining the last named means effective until all the idle ones of said plurality of switches have been set upon idle trunks. 85

3. In a telephone system, a plurality of automatic trunk hunting switches each having a test wiper, said switches being divided into groups, a motor magnet in each switch having one terminal normally connected to the associated test wiper, the other terminals of said magnets being normally disconnected, means for connecting a source of current to said test wipers when the trunks on which said wipers are standing become busy, and means including a relay common to all said switches for connecting the normally disconnected terminals of said magnet to said source of current to cause said switches to hunt for idle trunks, the last named means being arranged so that the magnets of one group only are connected up at any given instant. 95

4. In a telephone system, non-numerical switches, trunk lines accessible in common to said switches, wipers for said switches normally standing on a plurality of said trunk lines, and means controlled in accordance with the busy or idle condition of the trunk lines upon which said wipers are standing for causing the idle ones of said switches to automatically rotate in succession in search of idle trunks. 105

5. In a telephone system, a plurality of non-numerical trunk hunting switches divided into groups, a starting switch for starting said non-numerical switches one group at a time, and an operating circuit for said starting switch controlled jointly by means individual to said non-numerical switches and by means individual to the trunks accessible thereto. 115

Signed by me this 11th day of December, 1922.

GEORG GRABE.

In the presence of—
F. LUHBERGER,
A. KNITSCHER.
